Primary Examiner — Mary Ann Calabrese(74) *Attorney, Agent, or Firm* — Robert F. Zielinski(57) **CLAIM**

I claim the ornamental design for a moveable storage table, as shown and described.

DESCRIPTION

FIG. 1 is a front perspective view of a moveable storage table showing my new design.

FIG. 2 is a front elevational view thereof.

FIG. 3 is a rear elevational view thereof.

FIG. 4 is a right-side elevational view thereof.

FIG. 5 is a left-side elevational view thereof.

FIG. 6 is a top plan view thereof; and,

FIG. 7 is a bottom plan view thereof.

In the drawings, the broken lines show portions of the moveable storage table that form no part of the claimed design.
